UNITED STATES PATENT OFFICE.

JONOSUKE ARII, OF TOKYO, JAPAN.

APPARATUS FOR EXTRACTING OIL OR FAT.

Application filed March 24, 1921. Serial No. 455,172.

To all whom it may concern:

Be it known that I, JONOSUKE ARII, subject of Japan, residing at No. 22 Nishikubo Hiromachi, Shiba Ku, Tokyo, Japan, have invented new and useful Improvements in an Apparatus for Extracting Oil or Fat, of which the following is a specification:

This invention relates to an apparatus for extracting oil or fat from any material containing oil or fat, and consists of an inner cylinder provided with a number of lateral tubes, and an outer cylinder provided with a jacket through which steam passes for heating purpose, so arranged that the extraction of oil or fat takes place in the inner cylinder while in the outer cylinder the solvent is distilled and sent back into the inner cylinder. The object of this invention is to economize the cost of the work of extraction, to prevent waste of heat by utilizing the heat of the solvent and to increase the efficiency of the work.

The accompanying drawing shows a vertical section of the more important part of my apparatus.

To describe my apparatus more fully, (a) is the inner cylinder which is fitted within the outer cylinder (b) leaving a space between the two. The inside (A) of the inner cylinder (a) is the extraction chamber, and the space of the outer cylinder lying below the inner cylinder is the distillation chamber (B). The extraction chamber (A) is provided with two ports (1) and (2) which can both be hermetically closed, the former for feeding in the material and the latter to take it out after extracting oil or fat therefrom. Numerous lateral pipes (3) which pass through the wall of the inner cylinder (a) are for the vapor generated in the distillation chamber (B) to pass. These pipes also serve to form interspaces in the material which promote the circulation and penetration of the solvent and prevent congestration of the material. The inner cylinder (a) is provided with a false bottom (4) perforated with innumerable small holes. Below this false bottom (4) there is provided a coiled pipe (5), one end of which communicates with a main steam-pipe (8) through a valve (6) and a pipe (7), and the other end opens into air. A pipe (9) extending from the bottom (a') of the extraction chamber (A) is connected with a pipe (11) which communicates with the distillation chamber (B) through a three way

cock (10) and a siphon (12) which also serves as a gage. When desired the pipe (9) may be made by means of the three way cock (10) to communicate directly with the pipe (11) without going through the siphon (12). To the siphon (12) is fixed a test cock (13). A pipe (14) provided at the right shoulder of the inner cylinder communicates with a pipe (16) extending from the outer cylinder and also with another pipe (17) which leads to a condenser, by means of a cock (15); and by opening the cock (15) the communication between the extraction chamber (A) and the distillation chamber (B) can be opened. A pipe (18) leads from the discharge port of a reverse condenser (C) to the upper part of the inner cylinder. The pipe (18) is provided with a test cock (19).

The distillation chamber (B) is provided near its bottom with a coiled pipe (20), through which steam is introduced thereto, the coiled pipe being connected with the main steam pipe (8) through a valve (21). The solvent is fed into the distillation chamber from a tank by a pump through a pipe (23) provided with a valve (22). The bottom of the distillation chamber is covered with a steam jacket, into which steam is introduced from the main steam pipe through a valve (24). The steam jacket also communicates through a pipe (25) with the coiled pipe (5) at the bottom of the extraction chamber (A). (26) is a pipe through which oil or fat is drawn away from the distillation chamber (B), and the water condensed in the jacket is drained by a pipe which is provided with a valve (27). The distillation chamber has attached thereto a gage (28).

The condenser (C) is provided at its upper part with a pair of spiral pipes (29) and (30), either of which can be made to communicate with the pipe (17) by means of a three way cock (34). The other end (33) of the spiral pipe (29) leads to a second condenser (not shown in the drawings), whence to the tank in which solvent is kept; while the spiral pipe (30) leads into a cooling chamber (31) which is provided with numerous water tubes (32), whence to the extracting chamber (A) through the pipe (18).

To use this apparatus, put over the false bottom (4) at the bottom of the extraction chamber (A) a piece of felt or the like, and

then feed the extraction chamber from the port (1) with material such as bean crushed in a roll or the like, and close the port (1). Then open communication from the distillation chamber to the extraction chamber through the pipes (16) and (17), the spiral pipe (29), the condensing chamber (31) and the pipe (18). Also open the communication from the extraction chamber to distillation chamber through the tube (9), siphon (12) and the pipe (11). Then fill the distillation chamber (B) with solvent through the pipe (23). Then open the main steam pipe, and introduce steam into the steam jacket, into the distillation chamber (B) through the coiled pipe (20), and into the coiled pipe (5). Now, the solvent in the distillation chamber will be heated and evaporated; and the vapor passing through the pipes (3) which pass through the extraction chamber (A), finds its way via the pipe (17) and the spiral tube (30) into the condensing chamber (31), where it becomes condensed and drops down to the extraction chamber. The solvent thus condensed accumulates in the extraction chamber, steeps the material and extract oil or fat therefrom, and when the solvent accumulates in the extraction chamber higher than the height of the siphon (12), it together with the oil or fat, extracted, flows into the distillation chamber (B). In the distillation chamber the solvent will be again evaporated and take the same route as before, and thus repeatedly does the work of extracting oil or fat, leaving the extracted oil or fat, in the distillation chamber. When the oil or fat, in the distillation chamber accumulates to a certain amount or when all the oil or fat, contained in the material has been extracted, then close the connection of the tube (17) with the spiral tube (30) and open its connection with the other spiral tube (29). Also, close the connection of the tube (9) with the siphon (12) and open its direct connection with the tube (11). Then all the fluid contained in the extraction chamber (A) will flow into the distillation chamber (B), and the vapor of solvent will find its way not into the condensing chamber (31), but will go to another condenser via the spiral pipe (29), get condensed and eventually flow into the solvent tank.

According to my invention, the vapor of solvent is utilized to heat the extracting chamber. In fact a greater part of the heating work is done by it. Moreover, the provision of a large number of lateral tubes through the extraction chamber not only distributes the heat uniformly but greatly facilitates the contact of the solvent with the material, thus increasing the efficiency of extracting work.

I claim:

1. An apparatus for extracting oil or fat, 65 consisting of an inner cylinder fitted in an outer cylinder, leaving a space between the two cylinders, the said inner cylinder being pierced with a number of lateral pipes and the bottom of the said outer cylinder being 70 covered with a steam jacket, thus providing separately an extraction chamber and a distillation chamber, with means to open communication between the two, substantially as and for the purposes hereinbefore set forth. 75
2. An apparatus for extracting oil or fat, 80 consisting of an extraction chamber which is pierced with a number of lateral pipes, fitted within a distillation chamber, the bottom of which is covered with a steam jacket, 85 the bottom of the extraction chamber being connected with the upper part of the distillation chamber by means of a siphon, and the uppermost part of the distillation chamber being also connected with the uppermost part of the extraction chamber by means of a siphon, substantially as and for the purposes hereinbefore set forth. 90
3. An apparatus for extracting oil or fat, 95 comprising an extraction chamber, a plurality of tubes extending laterally through said chamber, a distillation chamber so disposed with relation to said extraction chamber that the latter is heated by vapor issuing from said distillation chamber, a steam jacket covering the bottom of said distillation chamber, a reverse condenser, and communicating means between said condenser and the extracting and distillation chamber.

In testimony whereof I have signed my 100 name to this specification in the presence of two subscribing witnesses.

JONOSUKE ARII.
